UNITED STATES PATENT OFFICE.

JOHN WEEKS, OF LOCUST VALLEY, NEW YORK, ASSIGNOR OF ONE-HALF TO HENRY C. DUDGEON, OF LOCUST VALLEY, NEW YORK.

HYDRAULIC JACK, PUNCH, AND SIMILAR MACHINE.

No. 876,920.

Specification of Letters Patent.

Patented Jan. 14, 1908.

Application filed November 24, 1906. Serial No. 344,833.

To all whom it may concern:

Be it known that I, JOHN WEEKS, a citizen of the United States, and a resident in Locust Valley, Nassau county, Long Island, 5 State of New York, have invented a certain new and useful Improvement in Hydraulic Jacks, Punches, and Similar Machines, of which the following is a specification, reference being had to the accompanying drawings, in which—

Figure 1 illustrates a vertical sectional view of the invention; Fig. 2 illustrates a detail of the knuckle construction, whereby the pump piston is reciprocated; Fig. 3 illustrates a detail of one of the valve tripping devices.

In the drawings hereof and in the following specification I will describe the invention as pertaining to a hydraulic jack of the up-right type, because the invention, although applicable as above stated to a variety of uses, may be conveniently and well illustrated in such a machine.

In hydraulic jacks of large power it is inevitable that the movement of the parts is slow. Consequently when the jack is in position, it requires sometimes an annoying amount of pumping and consumption of time before the head of the ram can be brought up 20 against its load and the lifting process commence, and under certain circumstances this delay is a matter of considerable consequence rather than mere annoyance. Several new forms of jacks have heretofore been invented 25 in the attempt to overcome the above stated objections, but all of them, so far as I know, have been found inoperative or objectionable for one reason or another. In this present invention, therefore, I have modified the construction of the jack so as to avoid the objectionable features of earlier forms in this direction and my improved apparatus is simple 30 in construction, free from mechanical embarrassments, possessed of all the desirable 35 attributes of such devices and of low cost.

Referring to the drawings, A, A, is the body of the jack, B is the ram, C the pump block screwed into the ram as shown, D the piston of the small pump provided with the 40 usual valve, bonnet, etc., E the lower valve provided with bonnet and spring, as usual, F, the force chamber, G the piston rod, H the head of the jack, I the socket in the jack, J, J, the knuckle on the shaft of the socket K.

L, L, are two slideways formed in the head 55 of the jack.

M is a cross-head which slides in the slide-ways L.

N is an enlarged pump bore at the upper end of the ram B, within which is the piston O 60 of a pump of much larger diameter than the regular pump, the piston of which is indicated by D.

P is a waterway made through the metal 65 of the ram.

Q is a check valve, R is a spring which normally seats the check valve.

S is a spindle supported in the metal of the head, as shown and provided with packing T and gland U, as usual, and with an actuating 70 lever or crank V, which is inclosed within a recessed casing W cast on the side of the head.

Y is a screw which engages in a recess Z cut in spindle S to prevent its outward movement.

a is a check valve in the piston O, b is a spring which normally reseats the valve a.

c is the usual perforated bonnet within which the spring b is located.

The spindle S is cut away, as shown at d, 80 in Fig. 3, so that the upper end Q' of the valve stem of the valve Q may rest against it and the cut away part of the spindle S is given cam shape, as shown in Fig. 3, so that when rotated a quarter turn, the valve stem 85 Q' will be depressed and the valve Q held off its seat. The valve stem Q' is supported and guided near its upper end by the perforated top of the valve block, the seat for this valve being near the lower end of the same block, 90 as shown.

The operation is as follows: The ram being located under its load, the pumping lever is operated as usual, whereupon the piston rod G, carrying both of the pistons, will be 95 reciprocated on lines parallel with the axis of the pump bores, because the slideways L will compel the cross-head M to so reciprocate. This is necessary because there are two pistons upon the same piston rod. Both 100 pumps get their supply of liquid from the same primary source, i. e., the reservoir in the head of the jack, the smaller one D, however, gets its supply immediately from the continuation of the pump chamber of 105 the larger pump, but the large one O receives its supply partly through the valve Q and water way P and partly through the

supplemental valve *a* located in the piston itself. It is not always necessary to have these two water supplies, but I prefer to add the supplemental valve in the piston because unless there is free liquid supply, the big pump is apt to work hard on the intake stroke and if the valve *Q* and waterway *P* are made large enough to avoid this objection, then these parts would sometimes be undesirably large. Upon the down stroke, the large pump *O* dominates the smaller pump *D* and forces a relatively large volume of liquid at each stroke down through the piston *D* and thence following the usual course, which need not be described, into the force chamber *F*. In this way the head of the jack is rapidly pumped up until it takes a bearing against its load and if the load is not so great but that it can be handled by the large pump *O*, then the work may be completed by it in much less time and with less labor than if effected through the use of the more powerful, but slower pump *D*. If, on the other hand, the load is heavy and beyond the ability of the large pump to handle, then the operator turns the crank *V* of the spindle over one quarter turn, and when the parts are in this position, the valve *Q* will be forced off its seat and held there by the cam action of the spindle *S* against the upper end of the valve stem *Q'*, thus putting the big pump *O* out of operation, its only effect being to churn a portion of the liquid back and forth through the waterway *P* and permanently open valve *Q*. Meantime, however, the small, but powerful pump *D* is performing its functions in the usual manner.

Those who are familiar with this art will appreciate the fact that because of my peculiar construction, I secure some important advantages, among them the following: The two pumps are located at the upper and lower ends respectively of the ram, the pump chamber for the large one being made in the body of the ram itself. From this construction flow the following advantages: No space is required in the head of the ram for the larger or upper pump. Thus there is no encroachment upon the liquid space. Again in my pump, owing to the fact that the pump chambers are connected by an open waterway, materially larger than the piston rod which passes through it, that waterway itself acts as part of the reservoir, thus materially reducing the bulk, cost and weight of the structure as a whole. Again my piston rod being smaller than the two pump chambers and waterway which connects them and making no contact with the walls of either of these spaces, it need not be highly machined, but may be left relatively rough throughout most of its area.

The simplicity and effectiveness of the construction and operation are apparent. The operator is called upon to do no act

whatever except to move the little crank of the spindle *S* to effect the substitution of the smaller, but more powerful and slower moving jack for the more rapid but less powerful one. No knowledge of the interior construction is required and any one of ordinary intelligence can operate the apparatus.

It will be obvious to those who are familiar with this art that the details of construction above described and illustrated may be departed from and still the essentials of the invention be retained. That which is shown and described is one form only in which the invention may be embodied and I therefore do not limit myself to such details.

Having described my invention, I claim:

1. The combination in a machine of the class stated of two pumps of different capacities, both located in the ram of the jack, one near the top of the ram, the other near the bottom thereof, both receiving their force liquid from the same reservoir and discharging it into the same force chamber.

2. The combination in a machine of the class stated of two pumps of different capacities, both located in the ram of the jack, one near the top of the ram, the other near the bottom thereof, the pistons of both pumps being mounted upon the same piston rod which is smaller than the pump chamber and connecting passages through which it passes, both pumps receiving their force liquid primarily from the same reservoir and discharging it ultimately into the same force chamber.

3. The combination in a machine of the class stated of two pumps of different capacities, the chamber of the larger one being cut in the body of the ram near the top thereof, the smaller one being located near the bottom of the ram, the pistons of both pumps being upon the same piston rod which is smaller than the pump chambers.

4. The combination in a machine of the class stated of two pumps of different capacities located at different ends of the ram, a water space connecting the two pump chambers, both of the pistons mounted upon the same piston rod which is smaller than the pump chambers and connecting water space, an ingress valve in the smaller piston and means to throw out of operation the larger pump.

5. The combination in a machine of the class stated of two pumps of different capacities located at different ends of the ram, the larger one discharging through an intermediate waterway into the smaller pump chamber, and thence through the piston of the smaller pump and means whereby both pumps may be simultaneously operated or the smaller one only.

6. The combination in a machine of the class stated of two pumps of different capacities located at opposite ends of the ram, a waterway in the ram connecting the pump

chambers, a piston rod smaller than the pump chambers and said waterway to which both the pistons are fastened, means to reciprocate the piston rod and pistons in lines 5 parallel to the axes of the pump bores, a waterway in the upper part of the ram connecting the pump bores with the reservoir, a valve controlling said waterway, a spindle actuated from the exterior of the structure 10 adapted to engage with the stem of the valve and hold it open, said pumps discharging into

the same force chamber, a check valve to prevent back flow from the force chamber and means to trip the check valve to permit back flow.

15

In testimony whereof I have signed my name to this specification in the presence of two subscribing witnesses.

JOHN WEEKS.
